UNITED STATES PATENT OFFICE.

ADAM P. WINIARSKI, OF NEW YORK, N. Y.

SQUEEGEE.

Application filed April 14, 1924. Serial No. 706,600.

To all whom it may concern:

Be it known that I, ADAM P. WINIARSKI, a citizen of the United States, residing at New York, county of New York, and State 5 of New York, have invented certain new and useful Improvements in Squeegees, of which the following is a specification.

This invention relates to means adapted for various purposes, but is especially designed for cleaning window panes, and for analogous purposes, and has for its main object to provide a device of the class described, that is simple in construction, effective in operation, and durable in use, adapted to effectively clean window panes in a comparative short space of time and with a minimum amount of effort.

With the foregoing, and other objects in view, hereinafter stated, the invention consists of the novel construction, combination and arrangement of parts hereinafter more specifically stated, and illustrated in the accompanying drawings, wherein is shown a device embodying the structure of the invention in its preferred form, but it is to be understood that changes, variations and modifications may be resorted to without departing from the scope of the invention.

In describing the invention in detail reference is had to the accompanying drawings, which form a part of this specification, wherein like characters of reference indicate corresponding parts throughout the several views.

As illustrated in the drawings:

Figure 1 is a side elevation of a device embodying the invention.

Figure 2 is a vertical transverse section taken on the line 2—2 of Figure 1.

Figure 3, is a side elevation, partly in section, of a device embodying the invention, showing the interior of the body of the device and;

Figure 4, is a diagrammatic view showing the device applied to a window pane.

As illustrated in the drawings, 1 represents a body or casing substantially cylindrical in cross section, and as shown in the drawings of varying diameter.

The body may be of uniform diameter throughout, however, if desired.

The body is preferably made of metal,

and is provided with longitudinal flanges, 2, and one or more blades of rubber 3, are secured at their inner margin between said flanges by means of rivets 4, or otherwise and extend preferably the full length of the body.

One end of the body may be closed by a head or plate 5, so as to form a container 60 to hold a sponge 6, cloth, or chamois, for use in connection with the device.

The body is also preferably provided with a bent-out portion or lip 7, to serve as a scraper to remove paint or other foreign matter from a pane of glass, and an aperture 8 may be formed in the body of the device, whereby the device may be hung on to a hook or nail to support the device when not in use.

When the device is in use, water is applied to a window pane, and the rubber blade drawn over the surface of the pane carrying with it all dirt and dust that has accumulated thereon. The soft yielding edge of the rubber blade not only removes all dust and dirt from the window pane, but also dries the surface of the pane without the use of a cloth.

If desired, soap and water may be applied to the surface of a window pane by means of a sponge, and after the pane has been gone over with the sponge, the water may be readily and quickly removed from the pane, and the pane dried of all moisture by means of the blade 3.

The device is also capable of being used for cleaning tables in restaurants, cafeterias and the like and is readily adapted for such use as it may be conveniently carried about in the pocket of the user when removing dishes and performing other operations.

What I claim as new and desire to secure by Letters Patent is,

A squeegee comprising a tapered tubular body of a diameter to be securely grasped in the hand, said body formed of a sheet of material with its meeting edges extending outwardly in parallelism, a squeegee element clamped between the aforesaid edges, and a closure for one end of said body.

In testimony whereof I have affixed my signature.

ADAM P. WINIARSKI.
